UNITED STATES PATENT OFFICE.

JOHN T. MORRIS, OF BALTIMORE, MARYLAND.

DESIGN FOR A CANE-HEAD.

SPECIFICATION forming part of Design No. 25,604, dated June 9, 1896.

Application filed May 12, 1896. Serial No. 591,298. Term of patent 34 years.

To all whom it may concern:

Be it known that I, JOHN T. MORRIS, a citizen of the United States, residing at Baltimore city, State of Maryland, have invented and produced a new and original Design for a Cane-Head; and I do hereby declare the following to be a full, clear, and exact description of the same, reference being had to the accompanying drawing, forming a part thereof.

My invention consists in a cane-head in representation of a man's head and neck, the neck being surrounded by a band, which is provided at its top and bottom, respectively,

with a bead, said band having the appearance of a ferrule.

In the accompanying drawing, illustrating my new design for a cane-head, *a* is the band surrounding the neck, and *b* the bead.

I claim as my invention—

The design for a cane-head herein shown and described.

In testimony whereof I affix my signature in presence of two witnesses.

JOHN T. MORRIS.
